To all whom it may concern:

Be it known that I, Philip Wenett, a citizen of the United States of America, residing in New York city, in the Borough of Manhattan, county and State of New York, have invented a new, original, and ornamental Design for a Dress, of which the following is a specification, reference being had to the accompanying drawing, forming part thereof, wherein,

Figure 1 is a front view of a dress showing my new design.

The characteristic feature of my design resides in the combination on the dress as shown of the appliqués superimposed on the skirt of the dress, presenting an appearance of falling leaves.

I claim:

The ornamental design for a dress, substantially as shown, and described.
